UNITED STATES PATENT OFFICE.

MAURICE MOSS, OF NEW YORK, N. Y.

DESIGN FOR AN ASH TRAY.

Application filed October 5, 1925. Serial No. 15,024. Term of patent 7 years.

To all whom it may concern:

Be it known that I, MAURICE Moss, a citizen of the United States of America, residing at New York, county of New York, and State of New York, have invented a new, original, and ornamental Design for Ash Tray, of which the following is a specification, reference being had to the accompanying drawing, forming part thereof.

The figure is a perspective view of an ash tray showing my new design.

I claim:—

The ornamental design for an ash tray as shown.

MAURICE MOSS.
